Attorney

UNITED STATES PATENT OFFICE.

GEORGE J. SMALLEY, OF HASTINGS, MICHIGAN.

TAPE REMOVER.

1,407,955.

Specification of Letters Patent. Patented Feb. 28, 1922.

Application filed May 8, 1921. Serial No. 468,061.

To all whom it may concern:

Be it known that I, GEORGE J. SMALLEY, a citizen of the United States of America, and resident of Hastings, in the county of Barry 5 and State of Michigan, have invented certain new and useful Improvements in Tape Removers, of which the following is a specification.

This invention relates to the treatment of 10 veneer and more particularly to a device intended for use in removing tape from veneer, the said invention including novel means for applying a solvent or moistening agent to soften the binding agent such as 15 the glue or adhesive which is used for securing tape to the back of the veneer. It is well known that in the treatment of veneer, the said veneer is taped together or mended, and after the work is ready to be 20 cleaned and the tape is to be removed, the apparatus of this invention is of great utility, since it provides novel means for softening the adhesive and dislodging the tape practically at one operation.

25 It is furthermore an object of this invention to produce an apparatus of the character indicated which can be manually operated; and the said invention furthermore contemplates the provision of novel means 30 for adjusting a scraper of the device to compensate for wear or for other conditions.

With the foregoing and other objects in view, the invention consists in the details of construction and in the arrangement and 35 combination of parts to be hereinafter more fully set forth and claimed.

In describing the invention in detail, reference will be had to the accompanying drawings forming part of this application 40 wherein like characters denote corresponding parts in the several views, and in which—

Figure 1 illustrates a view in elevation of the apparatus embodying the invention;

45 Figure 2 illustrates a sectional view on the line 2—2 of Fig. 1;

Figure 3 illustrates a front end view of the steam distributing head, with a fragment of the handle in elevation; and

50 Figure 4 illustrates a longitudinal sectional view of a fragment of the device.

In these drawings 5 denotes a pipe or hose for the supply of steam, which is attached to the hollow body 6. The body may 55 have annular ribs or threads 7 by which the hose may be attached to the body, and pref-

erably the end of the body remote from the hose is externally threaded as shown at 8.

A collar 9 is adjustably secured on the body by means of a set screw 10, and the said collar has a shank 11 preferably curved outwardly and rearwardly from the body, provided with a handle 12 by which the apparatus may be manipulated.

A sprinkling head 13 has discharge orifices 65 14 through which steam may escape, and preferably, these orifices are diagonal with respect to the longitudinal axis of the body, in order that when the said body is moved approximately horizontally or parallel with 70 the surface being treated, the steam or solvent will be discharged downwardly at an angle thereto to the surface of the veneer being treated. The head 13 has a rearwardly extending hollow boss 15 which is threaded 75 on the end of the body, and shoulders such as 16 are formed on the rear surface of the head on each side of the boss, the said shoulders being preferably slightly diagonal with respect to the longitudinal axis of the said 80 body.

A scraper 17 consists of a blade of proper dimensions having a cut-away portion, as at 18, forming a clearance for the hollow boss; and the said blade has slots 19 and 20 to 85 receive set screws 21 and 22 respectively, which are threaded in the shoulders of the nozzle or sprinkler head, in order that the blade may be adjusted with respect to the said head, the said adjustment being effective to compensate for wear, primarily, although it may be used for adjusting the position of the scraping edge with relation to the sprinkler head or nozzle.

Owing to the fact that the sprinkler head 95 is constructed in the manner stated with the shoulders at the rear thereof, it constitutes a means for mounting the scraper to accomplish the results stated, and of course, the adjustable mounting by which the handle is 100 connected to the body is a further advantage in that it allows for positioning the nozzle well in advance of the handle, if certain conditions of work justify this relation of parts.

It is believed that those skilled in the art 105 will appreciate the importance of the invention and its operation, for it will be apparent that steam which passes through the body or feed pipe, escapes through the sprinkler or nozzle and impinges the tape, 110 and the heat and moisture of the steam will result in softening the adhesive whether it

be glue or gum compounds which are usually employed on this class of tape, and that the tape which has undergone the change indicated is attacked by the scraper and dislodged or wholly removed, so that the process of removing the tape is completed at one operation.

I claim.

1. In a combined moistener and scraper, 10 a hollow body having means of steam supply connected to it, a sprinkler head attached to the opposite end of the body and having discharge orifices extending obliquely to the longitudinal axis of the body, shoulders 15 formed on the rear surfaces of the sprinkler head opposite the side having the orifices, screws threaded in the said shoulders, a scraper blade having a recess forming a clearance for a portion of the sprinkler head 20 and slots to receive the screws by which the scraper is adjustably secured in place, and a handle on the said body.
2. In a combined moistener and scraper, a body, a collar adjustably secured thereto, a 25 curved shank extending outwardly and parallel with the body having a handle, means for supplying steam to the body, a sprinkler

head connected to the body and having discharge orifices obliquely positioned with relation to the longitudinal axis of the body, a 30 hollow boss by which the sprinkler head is connected to the body, shoulders on the rear surfaces of the said sprinkler head, a scraper blade having a recess forming a clearance for the hollow boss and having slots, and 35 screws extending through the slots of the blade and anchored in the shoulders of the sprinkler head whereby the blade is adjustably secured in position.

3. In a combined moistener and scraper, a 40 body, a handle adjustably connected thereto, means at one end of the body for supplying steam to the body, a sprinkler head having a hollow boss threaded on the end of the body opposite the steam supply and having 45 discharge orifices for the steam, shoulders formed on the rear side of the body, and a blade having a clearance for the hollow boss, the 50 said blade having parallel slots and anchoring screws secured in the shoulders of the sprinkler head and projecting through the slots whereby the blade is held in different positions of adjustment.

GEORGE J. SMALLEY.
